UNITED STATES PATENT OFFICE.

SANFORD S. BURR, OF WINNETKA, ILLINOIS.

FOLDING BEDSTEAD.

SPECIFICATION forming part of Letters Patent No. 261,305, dated July 18, 1882.

Application filed June 14, 1882. (No model.)

To all whom it may concern:

Be it known that I, SANFORD S. BURR, of Winnetka, Illinois, have invented certain new and useful Improvements in Folding Bed-
5 steads, of which the following is a specification.

My invention relates to that class of folding bedsteads generally known as "wardrobe-bed-stands"—that is to say, bedsteads having a hinged bed capable of being turned up into a case or into upright position when not in use. The hinged bed usually has combined with or applied to it weights or springs which serve to counterbalance the weight of the bed when it is being turned up or down. These appli-
10 cations are necessary; but they are open to the objection that they render it difficult at the start to draw down the bed, and that they also cause the bed to close or fold up too rapidly and forcibly, unless care be taken to hold back
15 the bed by hand.

It is my object to provide means whereby the bed may be more easily managed and manipulated under these circumstances. To this end I combine with the hinged bed an inde-
20 pendently-hinged front, connected with the bed by a cord or equivalent connection, which will permit the front to turn down some little distance before the cord-connection is drawn taut. The front in this position serves both as
25 a weight and as a lever, which is conveniently placed for use, and acts through its cord-con-
nection with the bed to start and draw down the latter from its upright position. It also serves equally as a means by which the bed
30 when it is lifted can be held from closing too
35 forcibly.

The nature of my improvement and the manner in which the same is or may be carried into effect will be readily understood by reference
40 to the accompanying drawings, in which—

Figure 1 is a perspective view of a wardrobe-bedstead in folded condition containing my improvements. Fig. 2 is a like view of the same with the front partly unfolded or low-
45 ered. Fig. 3 is a sectional view, representing the bed partly lowered and the front com-
pletely lowered. Fig. 4 is a sectional view, rep-
resenting both bed and front completely un-
folded or lowered.

50 A is the case or frame, of ordinary or suitable construction.

B is the bed, hinged to the case at the point

a, provided with the usual counter-weights, b, and the hinged leg-frame c, which, when turned up as indicated in Fig. 1, constitutes the head-
piece of the wardrobe-front. 55

There is nothing essentially novel in the parts thus far described.

The hinged front hereinbefore referred to is shown at C. It may be hinged to any suit-
able part of the case or bed. In the present instance, in order to allow play for the spring
bed-bottom x, it is hinged to the lower part of
the case at a point, d, below the point a at
which the bed B is hinged, a space between
the front and the bed being thus afforded
when the two are unfolded for the play of the
bed-bottom, as indicated in Fig. 4. The front
C, at or near its upper end, is connected to the
upper end of the bed by cords e, or their equiva-
lent, the object being to obtain a flexible or
pliable connection between the two. The front,
when the bedstead is folded up, stands upright
and constitutes the front of the wardrobe, as
indicated in Fig. 1. 75

The action is as follows: When it is desired to lower the bed the front is opened and pulled down. Until it reaches the position indicated in Fig. 2, in which the cords are taut, it exercises no influence on the bed; but in this position it 80 acts as a weight to lessen the labor of starting the bed, and will, if made sufficiently heavy, serve to materially assist in lowering it. When it is pulled farther down, after reaching that position, it draws on the bed through the in-
termediary of the cords e and acts as a lever
to pull down the bed until it reaches its low-
est position, as indicated in Fig. 3, by which
time the bed has been so far turned down as
to render it easy to lower it. The front in this 90 position is supported by a hinged leg, f, at-
tached to it, which can be folded up out of the
way when the front is lifted. The person open-
ing the bedstead then takes hold of the bed
and lowers it from the position shown in Fig.
95 3 to that represented in Fig. 4, in which lat-
ter position it is supported and upheld by the
legs of the frame c. To close or fold up the
bed, reverse operation is gone through with.
The bed is lifted to the position shown in Fig.
100 3, in which position it requires but little, if
any, further lifting power applied to it in order
to bring it to upright position, and the oper-
ator, as the bed closes, prevents it from shut-

ting up too forcibly and quickly by pressing down on the front. As soon as the bed is in the upright position shown in Fig. 2 the front is raised and closed, as indicated in Fig. 1.

5 I have before stated that the front can, if desired, be hinged to the bed instead of the case. I would also state that, in lieu of using a front such as represented, I can use any other hinged appliance—as, for instance, a bar or other device connected to the bed by a cord or equivalent connection, and adapted to serve as a lever to draw or pull down the bed.

What I claim as new and of my invention is—

15 1. The combination, with the counterweighted folding bed and support or case to which the same is hinged, of a folding front or its equiva-

lent, hinged to said case or bed and connected with the bed by a cord or other pliable connection, substantially as and for the purposes hereinbefore set forth.

2. The combination of the case, the counterweighted bed hinged thereto, and the front, hinged also to the case at a point below the bed hinge and connected to the bed by a cord or other pliable connection, substantially as and for the purposes hereinbefore set forth.

In testimony whereof I have hereunto set my hand this 6th day of June, 1882.
